OREN B. SMITH, OF PALMER, MASSACHUSETTS.

Letters Patent No. 66,996, dated July 23, 1867.

IMPROVEMENT IN LOOM-PICKERS.

The Schedule referred to in these Letters Patent and making part of the same.

TO ALL PERSONS TO WHOM THESE PRESENTS SHALL COME:

Be it known that I, OREN B. SMITH, of Palmer, in the county of Hampden, and State of Massachusetts, have invented a new and useful Improvement in the Application of a Loom-Picker to its Staff; and I do hereby declare the same to be fully described in the following specification, and represented in the accompanying drawings, of which—

Figure 1 is a side elevation, and
Figure 2 a front view, and
Figure 3 a horizontal and transverse section of a picker and upper portion of a staff connected in accordance with my invention.

In the drawings, A denotes a picker, and B the head or upper part of its staff. The picker is composed of a series of pieces, $a a a$, of leather or raw hide, placed side by side on one another and cemented or otherwise fixed together. Sometimes they are not connected, except by the screw or devices by which they are held to the staff.

In fastening a picker to its staff by a screw, or by a screw and nut, it has been found very difficult, if not impossible, to prevent unscrewing of the screw or the nut during use of the picker by reason of the concussions or jar incident thereto. In carrying out my invention I so apply the screw-bolt and its nut to the picker and the staff that when the screw is set up into the nut neither of them can revolve independently of the part against which it is borne, whether that part be the picker or the staff. For this reason I form the nut, as well as the head of the screw, so as to clasp opposite surfaces of the parts against which they are to rest. In other words, I make the nut D and the head a' of the screw-bolt with ears $b b$, to lap on the sides of the parts against which they are to rest.

In applying the picker to its staff I first insert the screw-bolt through the former, and after having put the nut in place on the staff, I by means of the picker as a lever pass the screw into the picker and turn it into the nut so as to draw the picker and the staff together. Now as the tail part e of the picker will always be in the slot of the lay when the picker is in use, it will be impossible for the picker to be revolved, and unless it is revolved the disconnection of the picker and the staff cannot take place.

From the above it will be seen that the nature of my invention consists in so connecting or applying the screw-bolt, as well as the nut, to the picker or the staff in such manner as to be incapable of being revolved relatively to the part against which it is borne, the two being connected by revolving either the picker relatively to the staff or the staff relatively to the picker. The nut, as well as the head of the bolt, may be polygonal and sunk in the wood or the leather, but this is not so useful a mode of carrying out my invention as that where the head and nut are provided with ears, as exhibited in the drawings.

I claim as my invention the application of the screw-bolt and its nut to the picker and the staff, substantially as described, that is, so that when the screw is set up into the nut neither of them can turn independently of the part against which it is borne.

I also claim the construction of the screw and nut, viz., with the ears $b b b$ arranged on them as and for the purpose specified.

OREN B. SMITH.
